UNITED STATES PATENT OFFICE.

MORITZ COHN, OF NEW YORK, N. Y.

CORSET.

SPECIFICATION forming part of Letters Patent No. 224,076, dated February 3, 1880.

Application filed November 21, 1879.

To all whom it may concern:

Be it known that I, MORITZ COHN, of the city, county, and State of New York, have invented certain new and useful Improvements in Corsets; and I do hereby declare that the following specification, taken in connection with the drawings furnished and forming a part thereof, is a full, clear, and exact description of my invention.

10 My improvements relate to a certain variety of that class of corsets which have stiffeners or bracing-stays at the back. Some of these have had a single wide stiffener overlying the spine when worn, and others have had a pair of stiffeners or bracing-stays at the back, one stiffener on each side of the spine. Usually this latter class of corsets have been constructed in two parts, laced at the back across the spine, and it is to this particular variety of corsets that my improvements relate.

25 My invention consists in a back-laced corset provided at each side of the back-lacing with a stiffener or stay which is longitudinally divided except at its ends. The construction of these stiffeners may be varied—as, for instance, the simplest form of stiffener capable of use in accordance with my invention is composed of a single strip of suitable sheet metal centrally slotted longitudinally.

30 Another form embodies two separate strips of metal united together at each end by a transverse strip or bar.

35 Whichever way this stay may be constructed, it possesses not only the desirable characteristics of two separate stays, so far as independent flexure is concerned, for contributing to the ease and comfort of the wearer, but also the characteristic of a single stay of equal resistance to flexion, so far as relates to lateral support against the lacing strain, because of the 40 solidity of the stay at both of its ends, which serves to maintain the two side portions in a fixed position with relation to each other, instead of relying therefor solely upon the fabric of the corset, or upon additional material interposed between and surrounding two separate stays, as heretofore.

45 If the slot or space in my stay be only wide enough to receive a line of stitching and the 50 eyelets be placed wholly along the inner side or edge of the stay, the latter, although in one

sense two stays, resists the lacing strain much as if it were unslotted longitudinally; and if, as is preferable, said slot or space be wide enough to receive the lacing-eyelets, the lacing strain will be equally distributed, because of the solidity of both ends of the stay.

55 Referring to the drawings, Figure 1 represents, in rear view, a corset embodying my invention. Figs. 2 and 3 represent novel 60 back-stays constructed in approved forms in accordance with my invention.

These novel back-stays, as applied to corsets, occupy the same position with relation to the back edges of each half of the corset as 65 the merely stiffening strips of bone, or its equivalent, heretofore used in the same position; but to be in accordance with a certain portion of my invention they must be not only capable of affording the bracing effect desired 70 by reason of the material of which they are composed, and also because of their bulk and strength, but they must operate as a stay of considerable width at each end, and as two stays of lesser width centrally with capacity 75 for independent flexion, and also practically operate to equalize the lacing strain or distribute it among all the eyelets.

80 In Figs. 2 and 3 I show two modes of constructing such back-stays in their most approved form.

In Fig. 2 the stay A is composed of a single flat piece of steel of requisite thickness (which may be slightly varied in proportion to size of corset) with a longitudinal slot, a, 85 cut therein of a width slightly greater than the diameter of the barrels of the lacing-eyelets to be used therewith.

In Fig. 3 the same form is attained by the use of two parallel narrow strips, b, of steel, 90 united at both ends by a tie, c, riveted or clamped thereto. With this form of back-stay the desired degree of rigidity is attained throughout its length, it meantime possessing a capacity for independent flexion in each half 95 of the stay, which renders a corset provided therewith much more comfortable to the wearer than if the same degree of rigidity should be attained in a single strip equal to or even less in width than the two strips, as shown.

100 At the top and bottom of a stay of this form the two members thereof are practically as

- if solid; but midway either can freely yield independently of the other, thus enabling them to readily conform to the various attitudes of the wearer in walking or stooping. When applied to a sewed corset lines of stitching are preferably applied adjacent to the coincident edges of the slot *a*, as well as along the inner edge of the stay, which firmly incorporates it with the fabric.
- 10 In woven corsets woven pockets may be formed to receive the two members of the stay, Fig. 3, and the ties *c* thereafter applied; or a wide pocket may be provided for the stay, Fig. 2, and the inside lines of stitching thereafter applied. The lacing-eyelets *d* are located in the fabric which overlies the slot *a*, thus securing for them a firm foundation, from which they are seldom liable to be displaced. In some cases I graduate the flexibility of the 15 back-stays, for rendering it more flexible near each end than in the middle, by making the inner side of the stay wider in the middle than at the ends, as indicated by the dotted side lines in Fig. 3.
- 20 I am aware that it is not new for corsets to be provided with back-stays perforated to receive the lacing-eyelets, whereby the lacing strain on the eyelets is practically equalized and the eyelets prevented from being torn 25 from the corset; but the main object of my invention is to attain the same stiffening effect which could be attained with a wide stay or

spring, combined with the effect of two narrower springs having independent flexion centrally, but operating at and near each end as 35 a single wide spring.

The stays may be made of any suitable material, and steel is preferred by me, because of its durability and strength with a minimum of bulk.

40 Each half of the corset is provided with stays in accordance with my invention, the intervening lacing-cord overlying the spine of the wearer, thus locating the stays on either side over the muscles to which support is intended.

45 It will be seen that the independent flexure of the two sides of the slotted back-stay will be attainable if they be separated by a slot only wide enough to receive a stitch-line without space enough for the eyelets, which would therefore be placed in the fabric beyond the inner edge of the stay.

Having thus described my invention, I claim as new and desire to secure by Letters Patent—

50 A back-laced corset provided on each side of the lacing-space with a back stay or spring longitudinally slotted or divided except at its ends, substantially as described, and for the purposes specified.
